FABRICATED STAINLESS STEEL GATE VALVE

Wallace G. Rovang, Portland, Oreg., assignor to
Fabri-Valve Company of America, a corpora-
tion

Application April 16, 1949, Serial No. 87,865

1 Claim. (Cl. 251—327)

1

This invention relates generally to valves for controlling the flow of fluids and particularly to low pressure gate valves which are fabricated of stainless steel or having their seating surfaces protected by a chrome plating or otherwise protected against the action of the fluids passing therethrough.

The main object of this invention is to make a light weight valve for handling low pressure fluids such as are commonly found in paper mills.

The second object is to avoid the high cost of cast valves where large flows are handled at relatively low pressures.

The third object is to avoid the uncertainty of flaws and defects commonly found in cast parts.

The fourth object is to construct a valve of this type which will be easy to transport and handle for installation purposes.

The fifth object is to so construct the valve that pattern and other equipment commonly employed with casting process are not required and my valve adapts itself to the production of one or more valves of a given size or type without unduly increasing the cost of fabrication.

I accomplish these and other objects in the manner set forth in the following specifications as illustrated in the accompanying drawings, in which:

Fig. 1 is a side elevation of the valve.

Fig. 2 is an end elevation of the valve with parts broken away in section.

Fig. 3 is an enlarged fragmentary section taken along the line 3—3 in Fig. 2.

Fig. 4 is a fragmentary section taken along the line 4—4 in Fig. 3.

Fig. 5 is a fragmentary view of a gate and its guide in an open position.

Like numbers of reference refer to the same or similar parts throughout the several views.

Referring in detail to the drawings, there is shown a pair of tubular body members 10 whose opposite ends have outturned flanges 11 secured thereto by means of the welds 12.

The adjacent edges 13 are inclined in opposite directions and contain the valve seats 14 which are made of a material which will resist corrosion such as stainless steel or plated with a protective coating of chromium or other metal, depending upon the use of the valve.

On each tubular section 10 is rotatably mounted a ring 15 which is used to connect the valve to a pipe or fitting. The ring 15 is a cast section and, being movable, facilitates the alignment of the holes 16 with corresponding

2

holes in the member to which it is fastened.

Around one-half of the tubes 10 and overlapping the edges 13 is a band 17 which terminates in the parallel sides 18 which are joined by the saddle plates 19. The band 17 and plates 19 are secured to the tubes 10 by means of the welds 20.

A flange 21 is secured around the sides 18 and plates 19 by means of a weld 22.

10 The gate itself consists of a pair of converging disks 23 which are held in spaced relationship by the ring 24 and welds 29. The ring 24 is set inside of the outer edge of the plates to provide a welding corner, thereby forming a channel 26 around the gate.

15 Secured in the widest part of the channel 26 is a filler plate 27, on which is mounted a tubular shank 28 which is secured to the plate 27 and disks 23 by means of the welds 29. The shank 28 is threaded to receive the threaded sleeve 30 which is provided with a locking screw 31.

20 A stem 32 extends upwardly from the sleeve 30 and its head 33 is held between the plate 27 and sleeve 30.

25 Stiffening ribs 34 are held between the disks 23 by means of the spot-welds 35. At the narrowest portion of the channel 26 is welded a stop 36 which engages a stop screw 37 which is threaded through the band 17 and the thickening plate 38. A lock nut 39 is provided for the screw 37.

30 On opposite sides of the ring 24, between its widest and narrowest portions, are secured the curved slides 40 which can pass freely between the guides 41 secured along the band 17 and the straight sides 18. The purpose of the members 40 and 41 is to guide and support the gate when not in a closed or seating position.

35 In order to form a space for the gate in a raised or open position, there is provided a housing consisting of a rounded top 42 whose straight sides 43 are parallel with the sides 18. The ends 44 connect the sides 43 and top 42.

40 A flange 45 is provided at the open end of the housing by means of which it may be secured to the flange 21 by the bolts 46.

45 Stiffening ribs 47 are secured across each of the straight ends 44.

50 On the top 42 is secured a saddle base 48, upon which is bolted a standard 49, at whose upper end is disposed a plate 50 which has a sleeve 51, within which is rotatably mounted a nut (not shown), through which extends the threaded end 52 of the stem 32. The nut within 55 the sleeve 51 is attached to the bevel gear 53

which meshes with the pinion 54 which, in turn, is supported by a bracket 55 from the plate 50 and driven by the hand wheel 56. This form of construction for driving a gate valve stem is well known in the art.

At the top of the base 48 is secured a tubular stuffing box 57 having ears 58, to which are attached the eye bolts 59 which pass through the lugs 60 of the gland 61, by means of which the packing 62 may be compressed around the stem 32.

From the foregoing, it can be seen that the valve which I have described possesses a number of desirable characteristics not prominent in cast valves. It is light in weight, easy to fabricate, regardless of quantity, low in cost, uses thin walls making it practical to use more desirable non-corroding metals.

The stiffening rods 34 may be placed as shown in Fig. 5 or placed in fan shape with the lower ends closest together since it is this portion of the disks 23 which is subjected to the most violent action of the fluids passing through the valve.

I claim:

A low pressure gate valve constructed of rolled stainless steel plate comprising a pair of tubular body members in axial alignment, the adjacent faces of which are oppositely inclined and spaced to form a tapering channel therebetween, a band

covering the lower half of said channel and having a pair of parallel tangent sides, saddle plates covering said band sides, valve seats welded around the adjacent ends of said tubular members extending beyond their inclined edges, valve disks between said faces, means for actuating said valve disks, and valve guides mounted on the inner sides of said tangent sides and extending part way around the rounded portion of said valve.
